(57) **CLAIM**

We claim the ornamental design for a laser finger stop, as
shown and described.

DESCRIPTION

FIG. 1 depicts right-side view of a laser finger stop mounted
to a firearm showing our new design.

FIG. 2 depicts right-side view of the laser finger stop
showing our new design.

FIG. 3 depicts left-side view of the new design.

FIG. 4 depicts front view of the new design.

FIG. 5 depicts rear view of the new design.

FIG. 6 depicts top plan view of the new design; and,
FIG. 7 depicts bottom plan view of the new design.
The broken lines showing portions of the design in all
figures are included for the purposes of illustrating environment
and unclaimed features and form no part of the claimed
design.
